UNITED STATES PATENT OFFICE.

SAMUEL D. WORK, JR., OF NEW YORK, N. Y.

CURRENT-DISTRIBUTER.

1,386,980.

Specification of Letters Patent. Patented Aug. 9, 1921.

Application filed November 19, 1920. Serial No. 425,055.

To all whom it may concern:

Be it known that I, SAMUEL D. WORK, Jr., a citizen of the United States, and a resident of the borough of Queens, county of 5 Queens, city and State of New York, have invented a certain new and useful Current-Distributer, of which the following is a specification.

The invention relates to devices for distributing an electric current from a battery, generator, or other source of electric energy, to the sparking devices of the cylinder or cylinders of an internal-combustion engine. The device illustrated in the accompanying 10 drawings and described in the following specification and more particularly pointed out in the appended claims is designed particularly for use in connection with a Ford automobile, but it is to be understood that 15 the invention is not limited to such use, and the same may be carried out in connection with other ignition systems on other forms of automobiles and with internal combustion engines for purposes other than driving 20 automobiles.

The objects of the invention are to produce a device for the purpose described wherein perfect contact will be made at all times; wherein perfect breaking of the circuit will 25 be accomplished; wherein fouling of the contacts will be avoided; which will be cheap to manufacture; which will not easily get out of order; which will be easy of repair; which will be self contained; and wherein short 30 circuiting of the current will be avoided.

These and further objects will more fully appear in the following specification and accompanying drawings considered together or separately.

One embodiment of the invention is illustrated in the accompanying drawing, in which like parts in all of the several figures are designated by similar characters of reference, and in which—

Figure 1 is a rear elevation of a hood or casing embodying the invention, the engine cam shaft being shown in section.

Fig. 2 is a side elevation partly in section, the section being taken on the line indicated by 2—2 in Fig. 1.

Fig. 3 is a detail end elevation of what is

now considered the preferred form of cam, and

Fig. 4 is a detail side elevation of the same.

In the drawings 1 designates the cam shaft of an internal-combustion engine of any preferred type, and projects through the frame thereof into a shell or casing 2 secured to the outside of said frame thereof, and carried on the projecting end of the shaft is a cam which, in the embodiment of the invention illustrated consists of a cylindrical sleeve 3 having a cam portion 4, which latter is provided with a longitudinal keyway in which is inserted a key 5 preferably of hardened steel. The sleeve is provided with a pair of oppositely disposed radial notches 6, and is secured to the shaft 1 by means of a pin 7 which passes through the notches and the shaft.

Carried within the shell or casing is a plurality of radially disposed contacts each comprising a binding post 8 carried by and radially arranged within the cylindrical portion of the casing and suitably insulated therefrom, and carried by each binding post is an S-shaped spring contact member 9, which is secured by one of its legs to the binding post. Each binding post is insulated from the casing as by means of a collar of insulating material surrounding the same where it passes through the shell of the casing, and insulating washers engaging the inside and outside of the wall of the casing. The members are preferably formed of sheet 75 80 85 steel bent to form and hardened.

The members 9 are so proportioned and arranged that each, as a whole, projects radially inwardly from its supporting binding post 8 and into the path of the blade or key 5 when the latter is rotated by the rotation of the shaft 1. The inner leg of the member is preferably slightly inclined relatively to the path of travel of the blade or key 5 whereby the latter will always make elastic contact with the member.

The shape of the members 9 is important in that while there is considerable length to each member to provide for elasticity therein, the point of contact of the cam is substantially radial with the binding post, and

any vibration of the member is likewise on a substantially radial line. Each stationary member is isolated from each of the others, and one of the members cannot contact with 5 another and short circuit the device. There will be practicably no vibration of the members and such as does occur will be in the short inner straight end of the member which cannot vibrate to such an extent that it will 10 move out of the path of the blade 5 no matter how fast the latter may be moved.

Rigidly secured to each binding post 8 and within the casing 2 is a lead wire 10, and all of the lead wires are gathered into 15 a cable 11 which passes through an opening 12 in the lower side of the shell or casing and each wire is connected to a spark plug, as is common.

The shell, and with it, the contact members, is rotatably mounted on the engine casing concentrically with respect to the cam shaft 1, and is provided with the usual connections 13 with a steering wheel (not shown) or other control, whereby the contacts may be shifted to advance or retard 25 the spark, as is common.

The contact members 9 are completely isolated one from the other and danger of short circuiting is reduced to a minimum. While 30 the binding posts are illustrated as extending outside of the casing, it is to be understood that such binding posts may be entirely within the casing if desired.

In accordance with the provisions of the 35 patent statutes, the principle of the invention has been described together with the apparatus which is now considered to represent the best embodiment thereof, but it is desired to have it understood that the apparatus shown is merely illustrative, and 40 that the invention may be carried out in other ways.

Having now described the invention, what 45 is claimed and desired to be secured by Letters Patent, is—

1. A device of the character described, comprising a rotating contact member, and a stationary plicated spring contact member adapted to be engaged and wiped by the 50 rotating member, said spring member being arranged radially relatively to the rotating member.

2. A device of the character described, comprising a rotating contact member, and a 55 stationary plicated spring contact member anchored at one end and adapted to be engaged and wiped by the rotating member, said spring member being arranged radially relatively to the rotating member, said movable 60 member being adapted to engage the free end of the spring member.

3. A device of the character described, comprising a support, a plicated spring contact member carried by the support, a rotary

element, a contact member having a free end 65 carried by the element and adapted to periodically engage the spring member, said spring member being secured to the support by one end thereof, said rotary member engaging and wiping the free end of the spring 70 member.

4. A device of the character described, comprising a support, an ogee bowed spring contact member, carried by the support, a rotary element, a contact member carried by 75 the element and adapted to periodically engage the spring member, said ogee member being secured to the support by one of its legs, said rotary member engaging and wiping the other leg of the ogee member. 80

5. A device of the character described, comprising a cylindrical casing, an element concentric to the casing and adapted to rotate relatively thereto, a cam mounted on the element, a plurality of elastic contact 85 members carried by the casing and spaced apart, said members projecting radially inward, said members being of ogee form and secured to and insulated from the casing, one leg of each member being free and lying 90 in the path of travel of the cam whereby the latter may contact with the free legs of the members.

6. A device of the character described, comprising a cylindrical casing, an element 95 concentric to the casing and adapted to rotate relatively thereto, a cam mounted on the element, a plurality of elastic contact members carried by the casing and spaced apart, said members projecting radially in- 100ward, said members being of ogee form, one leg thereof being secured to and insulated from the casing, the opposite leg of each member being free and lying in the path of travel of the cam whereby the latter may 105 contact with the free legs of the member and means for completing an electric circuit between a member and the cam.

7. A device of the character described, comprising a cylindrical casing, an element 110 concentric to the casing and adapted to rotate relatively thereto, a cam mounted on the element, a plurality of elastic contact members carried by the casing and spaced apart, said members projecting radially in- 115ward, said members being of ogee form and secured to and insulated from the casing, one leg of each member being free and lying in the path of travel of the cam whereby the latter may contact with the free legs of the 120 members, and a conductor in electrical contact with each contact member within the casing.

8. A device of the character described, comprising a cylindrical casing, an element 125 concentric to the casing and adapted to rotate relatively thereto, a cam mounted on the element, a plurality of elastic contact
